UNITED STATES PATENT OFFICE.

ISADORE GOTTFIELD, OF DETROIT, MICHIGAN.

MACHINE FOR POLISHING STOVEPIPES.

SPECIFICATION forming part of Letters Patent No. 722,297, dated March 10, 1903.

Application filed November 17, 1902. Serial No. 131,668. (No model.)

To all whom it may concern:

Be it known that I, ISADORE GOTTFIELD, a citizen of the United States of America, residing at Detroit, in the county of Wayne and State of Michigan, have invented certain new and useful Improvements in Machines for Polishing Stovepipes, of which the following is a specification, reference being had therein to the accompanying drawings.

10 This invention relates to machines for polishing stovepipe; and its object is to provide a machine for the purpose which is adapted to receive lengths of pipe of any size or length and firmly hold and revolve the same, at the same time applying the liquid polish evenly to the pipe in such a manner that it will not be wasted or thrown about.

15 The invention also consists in providing means whereby the pipe is quickly and easily placed in the machine and taken therefrom and in providing a suitable receptacle for the liquid polish and a dauber for applying the same, which dauber is so arranged that the liquid is constantly stirred thereby; and it 25 further consists in making the parts adjustable and in providing certain other new and useful features.

20 To this end the invention consists in providing a suitable frame upon which is mounted a driven shaft provided with a conical head to engage one end of a length of pipe and an opposing longitudinally-movable shaft having a similar head to engage the opposite end of the pipe. Between the adjacent ends 35 of these shafts is provided a receptacle for the liquid blacking, and suspended within said receptacle or trough is a dauber pivoted to the frame to turn up against the pipe to apply the blacking thereto and at the same 40 time agitate the liquid in the trough.

The invention also consists in making the parts interchangeable and adjustable, and in the particular arrangement, construction, and combination of parts, all as hereinafter more 45 fully described, and particularly pointed out in the claims, reference being had to the accompanying drawings, in which—

Figure 1 is a side elevation of a device embodying my invention with the supporting-

frame partially broken away; Fig. 2, a plan view of the same with the upper portion sectioned on the line 2 2 of Fig. 1; Fig. 3, a section on the line 3 3 of Fig. 1; Fig. 4, a section on the line 4 4 of Fig. 1 looking toward the right, and Fig. 5 a section on the same line looking toward the left.

As shown in the drawings, A is a supporting-frame, formed of iron pipe, to which frame is secured the bed or table B, formed with a central longitudinal semicircular trough C and at each end upwardly-projecting standards D and D', having bearings D² at their upper ends for the shafts E and E', respectively. Fixed on the shaft E between the bearings D² and held against longitudinal movement thereby is a drive-pulley F, and each end of said shaft, which projects some distance beyond the bearings, is screw-threaded, the outer end to receive a collar G', against which the circular polishing-brush G abuts when screwed on the shaft, and the inner end, which is reduced to form a shoulder, is screw-threaded to receive the conical head H, secured thereon by a collar H³ at one side engaging the shoulder on the shaft and a nut H⁴ at the other side. The shaft E' extends some distance outside its bearings D², in which it is longitudinally movable, and on the inner end of said shaft is a conical head H', similar to the head H and held thereon by a collar I, secured to the shaft at one side, and a nut I' on the end of the shaft, which is set up against a shoulder I² on the shaft, said collar I forming a hand-hold to move the shaft longitudinally. Sleeved on the shaft E' between the bearings D² is a sleeve J, provided with a set-screw J', which is set up against the shaft to hold the same from moving longitudinally.

In each standard, directly beneath the inner bearing thereof, is formed a vertical bearing-slot K' to receive a bearing-sleeve K, said sleeve being formed with a flange K² at one end to engage the outer face of the bearing-slot and at its opposite end is screw-threaded to receive a nut K³ to engage the inner face of the same and secure the sleeve at any desired height in the bearing-slot. The trough C is

2

semicircular, with its edges extended a short distance above the face of the table B, and a board L', provided with trunnions L² to project into the bearing-sleeves K, hangs downward into the trough and is provided with a facing of wool or other material L³ to form a dauber L, which is turned up to contact the stovepipe by a bar M, provided with a handle at one end and attached at its opposite end to an arm M' on one of the trunnions L².

Secured to the table B at the corners of the trough are the castings or corner-irons N and N', the irons N being formed with slots to receive the ends of the spatter-boards O, which extend along the sides of the trough, and the irons N' with slots to receive the opposite ends of said boards and also the ends of a board extending across at the end of the trough to form a support P for the pipe, said board being concave at its upper edge to fit the convexity of the pipe.

The inclined faces H² of the heads H and H' are formed with corrugations, so that when the pipe is engaged with the head H at one end and placed on the support P at the other end and the shaft E' moved longitudinally to engage its head H' with that end of the pipe the pipe will not slip thereon, but will be firmly held between the heads H H' and rotated.

When pipes of smaller or larger diameter are to be polished, heads of the proper diameter are substituted for those on the machine, or these heads may be made with a longer tapering face to fit any size of pipe, and any of the ordinary lengths of pipe may be polished, as the shaft E' is of such a length that the head H' may be moved the length of the trough.

To cause the dauber to contact the pipe at the proper angle and place to do good work, it is adjusted up and down in its bearings by loosening the nuts K³ and adjusting the bearing-sleeves up or down in their bearing-slots, and when the facing L³ becomes worn in one place the dauber may be adjusted to change the point of contact. The trough being semicircular and the dauber moving in an arc within the trough keeps the liquid thoroughly agitated.

The rotary brush is used in polishing pipe-elbows; but if the pipe is rusty a buffer may be substituted for the brush, and it is obvious that any convenient power may be used to rotate the shaft H.

Having thus fully described my invention, what I claim is—

1. In a stovepipe-polishing machine, the combination of a conical head, means for rotating said head, and an opposing conical head adapted to be moved toward and from the rotated head to clamp a length of pipe between said heads.

2. In a stovepipe-polishing machine, the combination with two opposing heads one of which is movable toward and from the other

to clamp a length of pipe; of a trough, and a dauber adapted to project into the trough and to be turned to contact the pipe.

3. In a stovepipe-polishing machine, the combination with a table; of a shaft mounted in bearings on said table, a conical head fixed on said shaft, means for rotating said shaft, a longitudinally-movable shaft extending in axial line with said first-named shaft, a conical head mounted on the longitudinally-movable shaft, and means for holding the longitudinally-movable shaft in any adjusted position.

4. In a stovepipe-polishing machine, the combination with a table; of a semicircular trough in said table, shafts mounted in bearings on the table and extending above the trough, conical heads on said shafts, a dauber pivoted in bearings on the table and adapted to hang downward within the trough and means for turning the dauber to contact the pipe and to agitate the liquid in the trough.

5. In a stovepipe-polishing machine, the combination with a table provided with standards near its ends; of a shaft mounted in bearings on the standards at one end of the table, a shaft longitudinally movable in bearings on the standards at the opposite end of said table, conical heads on the opposing ends of said shafts, a trough in the table between said standards, a dauber pivoted at its ends on the standards and adapted to swing within the trough, and spatter-boards extending along the sides of the trough.

6. In a stovepipe-polishing machine, the combination with a table provided with standards at its ends; of a shaft mounted in bearings at the top of the standards at one end of the table, a pulley on said shaft, a longitudinally-movable shaft mounted in bearings at the top of the standards at the opposite end of the table, and heads on the opposing ends of said shafts, a trough in the table beneath the ends of said shafts, bearing-slots in the standards adjacent to the ends of the trough, bearing-sleeves in said slots each provided with a flange to engage the outer face of the bearing and a nut to engage the inner face thereof, a dauber and trunnions on said dauber to engage the bearing-sleeves.

7. In a stovepipe-polishing machine, the combination of a table formed with a central longitudinal trough and bearing-standards at each end of said trough; of a shaft journaled in the bearings on the standards at one end of the table and extended outward through said bearings, a conical head secured on one end of said shaft, a brush secured to the other end of the shaft, a longitudinally-movable shaft mounted in the bearings on the standards at the other end of the table, a conical head mounted on said longitudinally-movable shaft, a sleeve on said longitudinally-movable shaft between its bearings, a setscrew to secure the sleeve to the shaft, a

dauber journaled in bearings on the stand-
ards and adapted to turn within the trough,
an arm on the dauber and a bar pivoted to
said arm to turn the dauber, posts secured to
the table at each corner of the trough and
having grooves, spatter-boards engaging said
grooves and extending along the sides of the
trough, and a board extending across the end

of the trough and having a concave upper
side to form a support for the pipe. 10

In testimony whereof I affix my signature
in presence of two witnesses.
